UNITED STATES PATENT OFFICE.

JACOB B. CONOVER, OF JERSEY CITY, NEW JERSEY.

MILK-CAN.

SPECIFICATION forming part of Letters Patent No. 788,821, dated May 2, 1905.

Application filed January 20, 1904. Serial No. 189,841.

To all whom it may concern:

Be it known that I, JACOB B. CONOVER, a citizen of the United States, residing at Jersey City, in the county of Hudson and State 5 of New Jersey, have invented certain new and useful Improvements in Milk-Cans, of which the following is a specification, reference being had therein to the accompanying drawings, forming a part thereof.

10 My invention relates to milk-cans, and more particularly to the means for joining together the bodies and breasts thereof.

One of the objects of my invention is to effect a tight and rigid clamping together of 15 such parts, so that the structure at and in proximity to the juncture of the body and breast will be capable of resisting all ordinary and extraordinary strains and concussions and will maintain its integrity and 20 shape notwithstanding the rough usage to which milk-cans are frequently subjected.

Other objects of my invention are to effect economies in the cost of manufacture of milk-cans and to generally simplify and improve 25 the construction of milk-cans, as well as to materially increase their strength and durability.

My invention includes the provision of a 30 stiffening-ring clamping the edge or edges of an adjacent part or adjacent parts of the can with an angular joint, whereby it is rigidly held against inwardly-directed concussions or pressures.

My invention also includes the provision 35 of an interior clamping-lip on the stiffening-ring.

My invention also includes various improvements in the construction and combination of parts.

40 I will now describe the constructions embodying my invention illustrated in the accompanying drawings and will thereafter point out my invention in claims.

Figure 1 is an elevation, partly in section, 45 of the upper part of a milk-can. Fig. 2 is an enlarged section of the stiffening connecting-ring before attachment to the body and breast. Fig. 3 is an enlarged section of this ring and adjacent parts of the body and breast after attachment and clamping of the 50

parts together. Fig. 4 is a similar view of a modified construction. Fig. 5 is a similar view of another modified construction, showing at the upper part of the ring the initial position and at the lower part of the ring the 55 final position of the clamping-lips on the stiffening-ring. Fig. 6 is a similar view of another modified construction, showing at the lower part of the ring the initial position and at the upper part of the ring the final position of the clamping-lips of the stiffening-ring.

The milk-can, partly shown in the drawings, is of ordinary construction except at the juncture of the body *a* and breast *b*. At this 60 part of the can a ring *c* is provided, which takes the place of the ordinary reinforcing-hoop and performs the usual function of such hoop in imparting stiffness to the can and also performs the function of locking the 65 body and the breast together. The stiffening-ring *c* is separately shown in Fig. 2 in its condition before attachment to the adjacent parts of the can. It has an upper groove *d*, extending inward from the outer periphery 70 of the ring, and a lip *m*, the lower edge of which forms the upper wall of this upper groove, and it also has a lower groove *f*, also extending inward from the outer periphery of the ring, and a lip *o*, the upper edge of which 75 forms the lower wall of this lower groove. It also has an enlargement *r*, forming a bumper. The grooves *d* and *f* are originally of inwardly-tapering form, so that inwardly-extending flanges of the breast and body, respectively, may be readily turned into them. After a flange has entered its groove the corresponding lip is forced against and upon the flange to tightly grip the flange therein.

In Figs. 1 and 3 the parts are shown in attached condition. An inwardly-extending flange *e* at the lower end of the breast is clamped within the upper groove *d*. The lower portion *n* of the breast immediately above the flange extends outward from the 90 contour of the breast, having an outward and downward flare, and the outer upper portion of the lip *m* is correspondingly shaped, so as to fit tightly against the flaring portion *n* of the breast. The contour of the breast 95 100

merges into this flaring lower portion n without abrupt turns or corners, and the inner juncture of the upper end of the lip m of the stiffening-ring and of the breast presents no abrupt corner or pocket. In Figs. 1 and 3 an inwardly-extending flange g at the upper end of the body is shown as clamped within the lower groove f , and the lower clamping-lip o tapers downward and inward, and the part p of the body immediately below the flange is flaring to fit tightly the tapering lower part of the stiffening-ring, and this flaring portion of the body merges into the cylindrical part thereof without abrupt turns or corners. The angular bends of the flanges of the breast and body, the tight gripping of these flanges in their grooves, and the inner supports afforded by the lips m and o , respectively, effectively prevent any forcing inward of the breast or body in proximity to the stiffening-ring, and the stiffening-ring effectively joins together the body and breast. To assure continuity of the inner surface of the can, the inner junctures of the stiffening-ring and breast and body may be united by tin, solder, or other suitable cementing material, as indicated at h and i , respectively. Only light soldering would be required, and the joint could be effectively closed by tinning the parts after assembling.

In the modified construction shown in Fig. 4 a groove d' is provided only for the breast b' , and the breast extends outward and has a flange e' , which enters this groove. The clamping-lip m' of the stiffening-ring above the groove is of rectangular cross-section, and the outwardly-extending lower part n' of the breast immediately above the flange follows closely the contour of the lip m' and then merges into the ordinary breast shape. The stiffening-ring is here a hoop or band fitted over the upper portion of the body a' and having a bumper r' formed thereon and tapering inward toward its lower end to save weight and avoid an abrupt outer corner. The single inner juncture may be closed by tin or solder or other cementing material, as indicated at h' .

In the modified construction shown in Fig. 5 the breast b^2 extends outward and has a flange e^2 , which is turned downward into a corresponding upper groove d^2 , and the stiffening-ring c^2 has an upwardly-extending clamping-lip j , which is turned inward after the breast-flange has been inserted in the groove, thereby tightly locking the breast-flange, and the body a^2 extends outward at its upper portion and has a flange g^2 turned upward into a corresponding lower groove f^2 and locked by a clamping-lip k , which originally extends downward and which is turned

inward over the flange. The initial position is shown as to the upper clamping-lip j and the final position as to the lower clamping-lip k . The stiffening-ring is also a connecting-ring and has a bumper r^2 thereon, and the inner joints may be closed by tin or solder or other cementing material, as indicated at h^2 and i^2 , respectively.

In the modified construction shown in Fig. 6 the breast b^3 extends outward at its lower portion and has a flange e^3 turned upward and entering an upper pocket d^3 in the stiffening-ring c^3 . The stiffening-flange c^3 has a clamping-lip j' , which originally extends inward and which it turned down upon the breast-flange to tightly clamp it. The body a^3 extends outward at its upper part and has a flange g^3 entering a lower pocket f^3 in the stiffening-ring and is locked by a clamping-lip k' , similar to the upper clamping-lip. The initial position is shown as to the lower clamping-lip k' and the final position as to the upper clamping-lip j' . In other respects the construction is as heretofore described, a bumper r^3 being provided on the stiffening-ring c^3 .

It is obvious that various other modifications of construction may be made within the spirit and scope of my invention.

What I claim, and desire to secure by Letters Patent, is—

1. A milk-can having a stiffening-ring clamping the edge of a part of the can, such stiffening-ring having an annular groove receiving such edge and a clamping-lip forming one of the walls of such annular groove and exteriorly covered by such part.

2. A milk-can having a stiffening-ring clamping the edge of a part of the can, such part of the can having an end flange and a portion adjacent thereto extending outward from the contour of such part of the can, the flange extending at an angle to such outwardly-extending portion, and the stiffening-ring having a groove receiving such flange and a clamping-lip forming one of the walls of such groove and clamping such flange.

3. A milk-can having a stiffening-ring clamping the edge of a part of the can, such stiffening-ring having a groove receiving an inwardly-extending flange of such part and having a clamping-lip tapering downward to a smooth joint with such part in the interior of the can.

In testimony whereof I have affixed my signature in presence of two witnesses.

JACOB B. CONOVER.
